US00D870170S

(12) United States Design Patent **(10) Patent No.:** **US D870,170 S**
Hatano et al. **(45) Date of Patent:** **** Dec. 17, 2019**

(54) GRIPPER FOR INDUSTRIAL ROBOT

(71) Applicant: **NITTA CORPORATION**, Osaka-Shi (JP)

(72) Inventors: **Itaru Hatano**, Yamatokoriyama (JP); **Hirokazu Nitta**, Yamatokoriyama (JP)

(73) Assignee: **Nitta Corporation**, Osaka-Shi (JP)

(***) Term: **15 Years**

(21) Appl. No.: **29/693,803**

(22) Filed: **Jun. 5, 2019**

(57) CLAIM

The ornamental design for a gripper for industrial robot, as shown and described.

DESCRIPTION

FIG. 1 is a perspective view of a gripper for industrial robot illustrating our new design;

FIG. 2 is a bottom perspective view thereof;

FIG. 3 is a front view thereof;

FIG. 4 is a rear view thereof;

FIG. 5 is a right view thereof;

FIG. 6 is a left view thereof;

FIG. 7 is a top view thereof; and,

FIG. 8 is a bottom view thereof.

The gripper for industrial robot comprises a finger portion to grip an object.

The broken lines in the drawings depict portions of the gripper for industrial robot which form no part of the claimed design.
